UNITED STATES PATENT OFFICE

ZYGMUNT PEHEL, OF NEW YORK, N. Y., AND GEORGE ZYCH, OF LINDEN, NEW JERSEY

DOOR ALARM

Application filed December 20, 1930. Serial No. 503,656.

This invention relates to improvements in burglar alarm devices and more particularly to such a device that may readily be attached to a door knob spindle or the like, and it is 5 the principal object of our invention to provide a device by the use of which an alarm will be sounded whenever the knob spindle is rotated in either direction in an effort to open the door.

10 Another object of our invention is the provision of a burglar alarm device of comparatively simple and inexpensive construction, yet durable and highly efficient in operation.

A further object of our invention is the 15 provision of a burglar alarm device including a sounding member, sounded by novel and improved clapper members alternately engaging the sounding member upon the turning of the door knobs and their spindle.

20 A still further object of our invention is the provision of a burglar alarm device readily attached to and removed from a door knob spindle or other similar device, the body of which is equipped with means to 25 limit its swinging motions in either direction.

Further objects and advantages of our device will become more fully known as the 30 description thereof proceeds and will then be specifically defined in the appended claims.

In the accompanying drawings forming a material part of this disclosure:

Fig. 1 is a fragmentary edge view of a 35 door equipped with an alarm device constructed according to our invention.

Fig. 2 is a front elevation thereof.

Fig. 3 is a front elevation of the alarm device on an enlarged scale, partly in section.

40 Fig. 4 is a sectional end elevation of the alarm device, Figure 3.

As illustrated, a door 10 is equipped with the usual door knobs 11 and 12 on spindle 13.

45 The alarm device comprises a body 14 having an outer curved member 15 provided with a socket 16 allowing the passage of a clamp screw 17 formed at its outer end with a thumb piece 18 and at its inner end a curved 50 plate 18' for engagement of the door spin-

dle 13 to clamp the device to the same between said plate and a similarly curved seat 19 of body 14.

The sounding member 20 of a bell is attached by means of the pin 21 to a plate 22 secured to the door, and the outer threaded end of the pin carries the usual nut 23.

The lower end of body 14 is segmentally shaped and provided with teeth 24 in mesh with the teeth of a comparatively large and wide gear 25 on a spindle 26 secured in plate 22.

Smaller gears 27, 28, on spindles 29, 30, are in mesh with the teeth of the large gear 25 on opposite sides thereof.

The spindles 29, 30, carry each arms 31 extending in opposite directions from said spindles and having their ends slotted, as at 32, and in these slots the pins 33 of clapper members 34 are guided.

The body 14 is provided near its lower end with an arcuate horizontal slot 35 into which extends the pin 21, and the ends of the slot limit the lateral displacement of body 14.

The operation of our device will be entirely clear from the above description and inspection of the drawings, and it will be evident that the device can be readily attached by means of the clamp to the spindle of the door knobs.

If now the knobs are rotated in an effort to open the door, the toothed segment 24 of body 14 will turn gear 25 in either direction which through the engagement with the smaller gears 27, 28, will turn the same also and their spindles will rotate and operate the clapper members 34 to engage the sounding member 20 and thus give the alarm.

It will be understood that we have described and shown the preferred form of our device only as one example of the many possible ways to practically construct the same, and that we may make such changes in the general arrangement of our device and in the construction of the minor details thereof as come within the scope of the appended claims without departure from the spirit of our invention.

Having thus described our invention, what

we claim as new and desire to secure by Letters Patent is:

1. An attachment for door knob spindles comprising a body member adapted to be clamped to the spindle having an arcuate slot formed therein, a toothed segment at the lower end of said body member, a sounding member, a pin for receiving the same to a support passing through the slot in said body member to limit the lateral movements of said body participating in the turning movements of the door knob spindle, a gear in said sounding member in mesh with the teeth of said segment, smaller gears in mesh with said gear, and clapper elements operated from said smaller gears to alternately engage the sounding element upon the rotation of the door knob spindle.

2. In an attachment of the class described, a sounding member, a comparatively large and wide gear therein, means for operating said gear upon the turning of the knob spindle, smaller gears in mesh with said large gear at opposite sides thereof, spindles for said smaller gears, arms on said spindles extending in opposite directions therefrom and having their ends slotted, and clapper members guided and held in the slots of the ends of said arms adapted to alternately engage the sounding member to sound an alarm upon the rotation of said door spindle in either direction, and means for attaching the sounding member to a support.

Signed at New York, in the county of New York, and State of New York, this 19th day of December, A. D. 1930.

ZYGMUNT PEHEL.
GEORGE ZYCH.
